UNITED STATES PATENT OFFICE.

JOHN B. MILLER, OF MOUNT VERNON, OHIO.

COIN-CONTROLLED APPARATUS.

SPECIFICATION forming part of Letters Patent No. 512,205, dated January 2, 1894.

Application filed May 1, 1893. Serial No. 472,535. (No model.)

To all whom it may concern:

Be it known that I, JOHN B. MILLER, a citizen of the United States, residing at Mount Vernon, in the county of Knox and State of Ohio, have invented certain new and useful 5 Improvements in Coin-Controlled Apparatus; and I do hereby declare the following to be a full, clear, and exact description of the invention, such as will enable others skilled in the 10 art to which it appertains to make and use the same.

My invention relates to a coin-controlled apparatus for testing the force of a blow exerted by the fist, and has for its object to provide 15 novel means for rendering the machine inoperative until a coin of the proper denomination has been deposited upon which the apparatus is in proper condition to receive the impact of the blow, which, when delivered, 20 automatically registers the force of the same upon a suitable indicator, and to these ends my invention consists in the novel construction, arrangement of parts hereinafter fully described and afterward definitely pointed 25 out in the claims following, due reference being had to the accompanying drawings forming a part of this specification, wherein—

Figure 1 is a front elevation of my improved machine; Fig. 2 a vertical section thereof, 30 and Fig. 3, a front elevation, partly in section, the front of the casing being removed.

Referring to the drawings the letter A indicates the casing of the machine provided in its upper front portion with a glass or other 35 transparent pane B, through which may be viewed the indicator dial hereinafter described. In the lower portion of said casing is arranged a locked drawer C adapted to receive the coins.

40 D indicates a striking pad disposed within a suitable aperture a in the lower front portion of the casing and is designed to receive the impact of the blow. Said pad is rigidly affixed to one end of a hollow sleeve E which 45 at its outer end fits over a block or plug F.

Between the front end of the sleeve E and plug F is disposed a stiff spiral spring G which exerts its force to press the pad D outward. In order that the tension of the spring 50 may be adjusted a headed bolt H is centrally passed through the hollow sleeve E and plug F to the rear of the casing where it is pro-

vided with an adjusting nut g. The head end g of the bolt H is seated in a recess e in the forward end of the sleeve E, and by screwing up the nut g the tension of the spring G will be increased in a manner apparent, thus rendering it necessary to deliver a more forcible blow upon the pad D to register a given amount upon the indicator. 55

I indicates a reciprocating rack mounted in suitable bearings which gears with a pinion J, which in turn gears with a vertically movable rack K, and the upper end of the rack K gears with a pinion mounted on an arbor L carrying at its outer end an index 60 hand M which is adapted to indicate upon a dial N the force of the blow delivered upon the pad D, in the manner hereinafter described. 65

O indicates a coin chute of a proper size to receive a coin of the correct denomination to render the machine operative. 70

P indicates a lever pivoted between its ends in a bearing block p rigidly affixed to the sleeve E and is provided at one end with an inclined trough-shaped coin receptacle p'; said lever being heaviest at the opposite end, whereby the lever will normally rest in the position shown in Fig. 3. 75

Q indicates a push rod secured to the rear of the frame carrying the pad D, as clearly shown in Fig. 2, and adapted to freely pass within a hollow bore or longitudinal aperture formed in the rack I shown in dotted lines in 80 said figure of drawings. 85

The operation of the machine as above described is as follows: Let it be supposed that the parts are in the positions shown, which are the positions which they normally occupy. 90 Now if the pad D be struck a blow the force thereof will not be indicated upon the indicator N for the push rod Q will merely enter the hollow or tubular end of the rack I without moving the latter and consequently 95 without operating the indicator mechanism. Now if a coin of the proper denomination be inserted in the chute O, it will drop down into the coin receptacle p'; thus rocking the lever P and swinging its end p' up in front 100 of the end of the rack I, the rocking movement of the lever being arrested or limited by an arm or stop R. If a blow be now delivered upon the pad D, the end of the lever

P being interposed between the push-rod Q and rack I, said rack will be forced inward a distance equal to the distance traversed by the sleeve E and pad D against the tension of the spring G, and said rack will communicate its motion to the pinion J which in turn raises the rack K and rotates the index hand M, which indicates upon the dial the force exerted in delivering the blow upon the pad.

10 To hold the index hand at the indicating point I provide the following means. S indicates a bracket secured to the rear of the casing A and having rigidly secured thereto a strap T through which the rack K passes.

15 One end of a flat spring t is secured to the bracket S, the free end of which presses against the rack K which is thus held by friction and pressure between said spring and strap and holds the indicating mechanism in 20 position in order to allow the figures indicated upon the dial by the index hand to be read. The rack K is released by means of a push rod U which projects through the front of the casing and at its inner end engages the spring 25 t, so that by pushing said rod inward the spring t is forced away from contact with the rack K which then drops by gravity and through the medium of the pinion J returns the rack I to its normal position. When a 30 blow is delivered upon the pad D the jar communicates to the sleeve E, and consequently to the lever P and coin receptacle p, serving to throw the coin out of said receptacle and permitting it to fall into the drawer C.

35 In order that the indicator may be accurately set at zero point I provide an adjusting screw Y tapped through a suitable bracket y, the lower end of the rack K normally resting upon said screw and by means of which it 40 may be vertically adjusted to cause the indicator to be accurately set at zero point. The chute O is made of such a size that it will only admit coins of the proper size, and the lever P is so balanced that only a coin of sufficient weight will operate it.

45 As above constructed the parts need not be accurately constructed, as the tension of the spring G can at all times be very quickly and nicely adjusted as before described, and the 50 indicator can with equal facility be accurately set when the parts are assembled, after which its further adjustment will be unnecessary.

Having thus described my invention, what I claim is—

55 1. In a strength testing machine, the combination with a yielding pad carrying a push rod, a spring exerting a tension against said pad, and a hollow rack adapted to receive said push rod and acting to operate an indicator,

60 of coin controlled mechanism acting upon the reception of a coin to cover the open end of said rack, substantially as described and for the purpose specified.

65 2. In a strength testing machine, the combination with a yielding pad carrying a push rod, a spring exerting a tension against said pad, and a hollow rack adapted to receive said

push rod and acting to operate an indicator, of a rocking lever carrying at one end a coin receptacle which upon the reception of a coin causes said lever to cover the open end of said rack, substantially as described and for the purpose specified.

3. In a strength testing machine, the combination of the pad D and its hollow sleeve E, the spring G arranged therein, the push-rod Q carried by the pad frame, the rocking lever P provided in bearings on said sleeve and provided at one end with a coin receptacle p'; and the hollow rack I acting to operate an indicator, substantially as described, whereby upon the insertion of a coin the lever P operates to close the open end of said rack, for the purpose specified.

4. In a strength testing machine, the combination of the pad D and its hollow sleeve E, the spring G arranged therein, the push rod Q carried by the pad frame, the rocking lever P pivoted in bearings on said sleeve and provided at one end with a trough-shaped coin receptacle p'; the stop R, and the hollow rack I actuating an indicator, substantially as described, whereby upon the insertion of a coin the lever P operates to close the open end of said rack, for the purpose specified.

5. In a strength testing machine, the combination of the pad D and its hollow sleeve E, the spring G arranged therein, means for adjusting the tension of said spring, the push rod Q carried by the pad frame, the pad frame, the hollow rack I actuating an indicator, and coin controlled apparatus acting to close the open end of said rack upon the insertion of a coin, substantially as described and for the purpose specified.

6. In a strength testing machine, the combination of the pad D and its hollow sleeve E, the block F, the spring G arranged within said sleeve, the headed bolt H secured to said hollow sleeve and passing through said block and provided with an adjusting nut g, the push rod Q carried by the pad frame, the hollow rack actuating an indicator, and coin controlled mechanism acting to close the open end of said rack upon the insertion of a coin, substantially as described and for the purpose specified.

7. In a strength testing machine, the combination of the pad D carrying a push rod Q, the spring G exerting a tension against said pad, of the hollow rack I, pinion J, and rack K meshing with a pinion on the arbor of an index hand, and coin controlled mechanism acting to close the open end of said hollow rack upon the insertion of a coin, substantially as described and for the purpose specified.

8. In a strength testing machine, the combination of the pad D carrying a push rod Q, the spring G exerting a tension against said pad, of the hollow rack I, pinion J and rack K meshing with a pinion on the arbor of an index hand, means for holding said rack K in its raised position until released by hand, and

coin controlled mechanism acting to close the open end of said rack I upon the insertion of a coin, substantially as described and for the purpose specified.

- 5 9. In a strength testing machine, the combination with pad D carrying a push rod, the spring G, the hollow rack I, pinion J, and the rack K meshing with a pinion on the arbor of an index hand, of the strap T embracing the
10 rack K, a spring t pressing against said rack and engaged by a rod U which serves to release it, and coin controlled mechanism acting to close the open end of said rack I upon the insertion of a coin substantially as described
15 and for the purpose specified.

10. In a strength testing machine, the com-

bination of the pad D carrying a push rod, the spring G, the hollow rack I, pinion J, and the rack K meshing with a pinion on the arbor of an index hand, coin controlled mech- 20
25 anism acting to close the open end of the hollow rack upon the insertion of a coin, and the set screw V bearing against the lower end of the rack K by means of which said rack may be adjusted to accurately set the index hand, substantially as shown and described.

In testimony whereof I affix my signature in presence of two witnesses.

JOHN B. MILLER.
